(57) CLAIM

The ornamental design for housing for a physical fitness apparatus, as shown and described.

DESCRIPTION

FIG. 1 is a perspective view of housing for a physical fitness apparatus showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view showing grips with the housing of FIG. 1 thereof;

FIG. 9 is a perspective view showing a person to use the physical fitness apparatus by feet thereof; and,

FIG. 10 is another perspective view showing a person to use the physical fitness apparatus by hands.

The broken lines in FIG. 8, FIG. 9 and FIG. 10 are for illustrative purpose only and forms no part of the claimed design.
